CLAIM

The ornamental design for a work lamp, as shown and described.

DESCRIPTION

FIG. 1 is a perspective view of a work lamp showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view thereof in an alternative configuration of use.

The broken lines illustrate portions of the work lamp that form no part of the claimed design.
